UNITED STATES PATENT OFFICE.

JOSEPH B. LOWELL, OF EVERETT, MASSACHUSETTS.

APPARATUS FOR LOCKING CAR-DOORS.

1,037,502.

Specification of Letters Patent. Patented Sept. 3, 1912.

Application filed June 28, 1912. Serial No. 706,409.

To all whom it may concern:

Be it known that I, JOSEPH B. LOWELL, a citizen of the United States, and resident of Everett, county of Middlesex, State of Massachusetts, have invented an Improvement in Apparatus for Locking Car-Doors, of which the following description, in connection with the accompanying drawing, is a specification, like characters on the drawing representing like parts.

This invention has for its object the production of improved and efficient apparatus for locking the doors of freight cars and the like, whereby, when the door is locked it cannot be unlocked from the exterior of the car until fluid under pressure has been supplied to the locking mechanism. Devices of this general character are not broadly new, but they are all open to serious practical objection owing to the mode of operation thereof.

In one type of locking mechanism the fluid under pressure is obtained from a reservoir on the car connected with or forming a part of the air-brake mechanism, but the vital objection to this arrangement is due to the fact that the air will remain under pressure for but a few hours, even under the best of conditions. A car so equipped cannot be opened except by coupling up with a locomotive or some other supply of air after the car has been cut off for a comparatively short time, and if the car to be opened is in the middle of a string of cars all cars between the locomotive and the car to be opened must be coupled up. If a hand pump is used there is nothing to prevent such use by unauthorized parties, so that the locking of the car is not properly safeguarded. Other forms of pneumatically opened locking devices are so constructed that they can be opened only by coupling up the car and a locomotive, the air pressure requisite to unlock the car being altogether under the control of the engineer. This arrangement provides ample safeguard against unauthorized unlocking of the car, but it is objectionable because the car must be coupled to the locomotive air-brake system before it can be unlocked, and in a large yard the inconvenience is so great as to make the construction impracticable of adoption.

In my present invention the door locking

mechanism is released by the admission of 55 a fluid, such as air, under pressure from any suitable source of supply, which may be a hand pump, a locomotive, or otherwise, but the apparatus is so arranged that the connection can be made only by the use of 60 a detachable coupling member or key, which is under the control of the yard-master or other official. When the said coupling member or key is applied to the conduit on the car leading to the locking mechanism a 65 valve in such conduit is opened automatically and a free passage of the air under pressure is provided. The removal of the key causes the valve to close automatically, and no matter what pressure is applied to 70 the conduit the locking mechanism is unaffected unless the valve can be opened and maintained open, and this cannot be done without the key.

The mechanism is simple and strong, it 75 is inexpensive to manufacture, and is not liable to get out of order.

The various novel features of my invention will be fully described in the subjoined specification, and particularly pointed out 80 in the following claims.

Figure 1 is a view of a portion of the interior of a freight car, partly in vertical section, showing a door locking mechanism applied thereto embodying one form of my 85 invention, the door being shown as locked; Fig. 2 is a right hand side elevation of the casing containing the locking devices proper, with the cover removed; Fig. 3 is a horizontal sectional detail on the line 90 3-3, Fig. 2; Fig. 4 is an enlarged longitudinal section of the inlet end of the conduit connected with the locking devices, the normally closed valve being shown in elevation; Fig. 5 is a similar view of the coupling member or key, detached; Fig. 6 is a much enlarged cross-section of the key on the line 95 6-6, Fig. 5, looking toward the right; Fig. 7 is an enlarged outer end view of the extension on the conduit, to be referred to; Fig. 8 is a longitudinal sectional view of the coupling member or key temporarily connected with the conduit, showing the manner in which the conduit valve is opened at such time.

Referring to Fig. 1, A represents a portion of the side wall of a freight or box car, B is the sliding door, and C is the usual up-

right post at the side of the doorway, all viewed from the interior of the car. The door has a hooked latch D pivotally mounted thereon at E, and said latch is limited as to its angular movement by a segmental stop F, the latch being of sufficient length when in its locking position to extend a considerable distance beyond the edge of the door.

- 10 In the present embodiment of my invention the post C is cut out or recessed to receive a casing 1, preferably of cast iron, having a heavy face plate 2 which is mortised into the post, said face plate having an elongated upright slot 3 for the passage therethrough of the latch D. The plate 2 within the casing has an upright guide 4 formed thereon, for the reception of a vertically slidable keeper 5, the lower end thereof engaging the latch behind the latch shoulder, as shown in Fig. 1, to retain the door locked. A stud 6 on the keeper projects through an upright slot 7 in the guide 4, offset laterally from the latch, and said stud is pivotally connected with the upper end of a rod 8 having an attached piston 9 slidable in a cylinder 10. This cylinder has an apertured head for the rod 8, and the lower end of the cylinder fits air-tight in a base 11 on the bottom of the casing 1. A coiled spring 12, Fig. 1, between the head of the cylinder and the piston acts normally to depress the keeper 5 in locking position, undue descent of said keeper being limited by engagement of the stud 6 with the bottom of the slot 7.
- 15 A cover plate 13, Fig. 1, is attached to the back of the casing by screws 14, thereby inclosing within the casing all of the parts of the locking mechanism so far described.
- 20 The cylinder 10 has permanently attached to it below the piston a conduit 15, which is continued inside the car to any convenient part thereof, as for instance, one of the end posts G, the latter having a hole 16 therein, see dotted lines Fig. 1, covered at its outer end by a swing plate 17. Inside the post the conduit is supported and fixedly held by a tubular support 18 attached to the post. At a point within this support the conduit 15 is externally screw-threaded, at 19, Figs. 4 and 8, and provided with a valve seat 20, with which co-operates a valve 21, and beyond the valve seat the conduit is reduced in diameter to present a tubular extension 22 having inlet ports 23 adjacent the valve seat. The extension has near its outer end a fixed diaphragm 24 provided with a square hole through which passes freely the spindle 25 of the valve, square in cross section and threaded on its longitudinal edges at its outer end, which projects slightly beyond the diaphragm when the valve is seated by spring 26. Ordinarily the expansibility of the spring maintains the valve 21 seated, so
- 25 that there is no communication through the

inlet ports 23 to the conduit 15 and cylinder 10, but when the spindle 25 is drawn to the right, Fig. 4, the valve will be unseated, as shown in Fig. 8.

I will now describe the coupling member or key by which the valve is opened when it is desired to retract the keeper 5 of the locking mechanism. Referring to Fig. 5 said member or key is shown as a tube 27 threaded internally at its inner end at 27* for threaded engagement with the portion 19 of the conduit, the outer end of the tube being reduced at 28 and preferably having a usual form of spring-valve 29 to close the seat 30. The end 28 is internally threaded for attachment to the usual nipple of an air pump tube, or with any other suitable source of air under pressure, and when not in use the part 28 may be closed by a screw cap 31.

Within the member 27 I mount a nut 32 having apertures 33 and a central hub 34 internally threaded at 35, said hub being attached to one end of a spring 36. Said spring at its opposite end is fastened to the end of the member 27, permitting the nut 32 to move against the spring longitudinally in the member 27 but preventing rotation of the nut. To limit spring induced movement of the nut I provide stop pins 37, Figs. 5 and 6, driven through the tube 27, but any other form of stop can be used.

Referring to Fig. 1, when the latch D is moved down into substantially horizontal position and the door B is shut the nose of the latch passes through the slot 3 of the face plate into the casing 1, lifting the keeper 5 against spring 12 until the keeper can drop behind the shoulder of the latch, locking the door. The locking action is thus automatic, the door being shut from the outside, and when locked it is inaccessible for opening from the exterior of the car unless the keeper is lifted by air pressure introduced into the cylinder 10 beneath the piston 9.

The coupling member or key 27 is in the custody of the yard-master or other authorized person, and when a car is to be opened such person takes the key and preferably an ordinary bicycle pump, and proceeds to the car. The cover 17 is swung to one side and the threaded end of the key is inserted in the hole 16 and screwed onto the part 19 of the conduit. As the key is thus moved inward around the extension 22 the hub 34 of the nut 32 is caused to engage the threaded end of the spindle 25, and as the rotation of the key is continued the co-operation of the nut and spindle cause the latter to be moved outward, unseating the valve 21, as shown in Fig. 8. The nut 32 is pushed toward the outer end of the key 27 during this procedure, but the spring 36 gives it the requisite backing to keep up to its work. When the threaded engagement of the key and

conduit is complete the parts are in the position shown in Fig. 8, said key fitting tightly the conduit, but there is a free passage for air through the key, between it and the extension 22 to the inlet ports 23 and thence through the open valve seat 20 to the conduit 15 and the cylinder 10, the apertures 33 in the nut permitting the air to pass. If now the outer end of the key is connected with any suitable supply of air under pressure, and it is immaterial whether it be a hand pump or an air brake mechanism on a locomotive, the air under pressure will flow through the key and into the conduit 15 and thence to the cylinder 10 elevating the piston and lifting the keeper 5 out of engagement with the latch D so that the door can be opened from the exterior of the car. When the releasing air has been applied and has performed its function, namely, to effect the release of the door latch, the key is removed by unscrewing it from the threaded part 19 of the conduit. As the key is unscrewed the nut 32 is unscrewed from the threaded valve spindle 25 and immediately the spring 26 re-seats the valve, absolutely closing the conduit.

From an inspection of Fig. 4, it will be manifest that even should the projecting end of the valve spindle be grasped by a suitable tool and pulled outward, to open the valve, there would be nothing gained by such procedure, because no air under pressure could be transmitted at the same time to the conduit. The only way for air to be transmitted through the conduit is to connect the latter with a source of air supply simultaneously with the opening of the valve, and that is effected by the combined coupling member and valve opening device.

So far as concerns the valve 29 in the outer end of the key, shown in Fig. 5, it will be obvious that it is not an essential feature of the invention, for the operation of the device is precisely the same if such valve be omitted. It is convenient, however, to have such a valve, as it keeps dirt from entering the key, and furthermore, when using a hand pump to supply the compressed air the valve 29 acts as a check valve.

In Fig. 8 I have shown the cap 31 removed, and the nipple of the tube connected with the source of compressed air is shown in operative engagement with the part 28 of the key.

From the foregoing description and the drawing it will be manifest that the locking mechanism cannot be supplied with releasing air unless the coupling member or key is used, and interposed between the accessible inlet end of the conduit and the source of air under pressure.

An ordinary bicycle tire pump will be found ample for the purpose of operating the locking mechanism, as only a few pounds

pressure is required, and while the locking mechanism can be operated by train pipe pressure if convenient, it can be only in connection with the coupling member or key.

My invention is not restricted to the precise construction and arrangement of the locking mechanism, and various changes or modifications in details of construction and arrangement may be made by those skilled in the art without departing from the spirit and scope of my invention, but so far as I am aware, it is broadly new to provide a safety device such as the coupling member or key hereinbefore described for use in connection with a door locking mechanism of this general character, and the same is claimed broadly in the claims hereunto annexed.

Having fully described my invention, what I claim as new and desire to secure by Letters Patent is:

1. The combination with a car and its sliding door, and a pneumatically released door-locking mechanism inaccessible from without the car when the door is locked, of a conduit communicating with and to supply releasing air to said mechanism and having an accessible inlet end, a normally closed valve in the conduit, and a detachable coupling key having means to open the valve when said key is applied to the inlet end of the conduit, thereby to establish communication with the locking mechanism, said key being adapted for temporary connection with a source of air under pressure to couple the locking mechanism therewith when the conduit valve is opened by the key.

2. The combination with a car and its sliding door, and a pneumatically released door-locking mechanism inaccessible from without the car when the door is locked, of a conduit communicating with and to supply releasing air to said mechanism and having an accessible inlet end, a normally closed valve in the conduit, a detachable, tubular coupling key applicable temporarily to the inlet end of the conduit and adapted for temporary connection at such time with a source of air under pressure, and means rendered operative by the application of said key to the conduit to open the valve therein and maintain it open while the key and conduit are connected.

3. The combination with a car and its sliding door, and an automatically locking mechanism to retain the door closed, of a permanently attached conduit to supply releasing air to said mechanism, a normally closed valve in the conduit, having an exposed spindle, a detachable, tubular coupling member adapted for temporary attachment to the conduit and to a source of air under pressure, said member having means for threaded engagement with the conduit, and means within the coupling

member to engage the valve spindle and unseat the valve when said member is caused to have engagement with the conduit.

4. The combination with a car and its sliding door, and an automatically locking mechanism to retain the door closed, of a permanently attached conduit to supply releasing air to said mechanism, the outer end of the conduit having a valve-seat therein 10 and a tubular extension beyond the seat, provided with an inlet port, a spring-controlled valve normally held on the seat, to close the conduit, a tubular coupling member adapted for detachable threaded engagement with 15 the conduit beyond the inlet port, and means within said member to coöperate with and unseat the valve when the said member is in engagement with the conduit, whereby air from a source of supply connected with 20 the outer end of the coupling member may pass through the latter to the conduit through the port and the open valve seat.

5. The combination with a car and its sliding door, and a pneumatically releasing 25 door-locking mechanism inaccessible from without the car when the door is locked, of a conduit communicating with and to supply releasing air to said mechanism and having an accessible inlet end, said conduit 30 having a valve seat therein, a tubular extension beyond the valve seat, provided with an inlet port, and a spring-seated valve having a threaded spindle longitudinally movable in the extension, a tubular coupling member adapted for temporary connection at its outer end with a source of air under pressure and threaded at its inner end for connection with the conduit beyond the 35 inlet port, and a yieldingly-sustained and 0 apertured nut in said coupling member and rotatable therewith, to engage the valve spindle and unseat the valve when the coupling member is screwed onto the conduit, whereby air from the source of supply can 5 pass from the coupling member to the con-

duit through the inlet port only when said coupling member is operatively connected with the conduit.

6. The combination with a car and its sliding door, and a pneumatically released 50 door-locking mechanism inaccessible from without the car when the door is locked, of a conduit communicating with and to supply releasing air to said mechanism and having an accessible inlet end, a normally closed 55 valve in the conduit, a detachable tubular coupling member adapted for threaded engagement with the accessible end of the conduit, to connect it temporarily with a supply of air under pressure, and means acting only 60 when the coupling member is attached to the conduit to open the valve and maintain a free passage through the said coupling member and conduit to the locking mechanism. 65

7. A pneumatically controlled lock for sliding doors, comprising a casing having a slot for the entrance of the door-latch, a spring-actuated keeper slidably mounted in the casing to engage the latch when the latter enters the casing, an air cylinder having a piston, a connection between the latter and the keeper, to move said keeper into latch-releasing position, a conduit leading into the cylinder, to admit fluid under pressure 75 thereto to effect releasing movement of the piston, a normally closed valve within said conduit, and a detachable key to open the valve when said key is applied to the conduit, said key being adapted for connection 80 at such time with a suitable source of fluid under pressure. 80

In testimony whereof, I have signed my name to this specification, in the presence of two subscribing witnesses.
